ATTYS.

UNITED STATES PATENT OFFICE.

DANIEL J. GOLDEN, OF BROCKTON, MASSACHUSETTS.

SPORTING-SHOE.

1,390,698.

Specification of Letters Patent. Patented Sept. 13, 1921.

Application filed September 24, 1920. Serial No. 412,493.

To all whom it may concern:

Be it known that I, DANIEL J. GOLDEN, a citizen of the United States, residing at Brockton, in the county of Plymouth and 5 State of Massachusetts, have invented new and useful Improvements in Sporting-Shoes, of which the following is a specification.

This invention relates to shoes such as are worn by base-ball players, the bottom of the 10 shoe being provided with spurs adapted to afford a secure foothold. The object of the invention is to provide a sporting shoe, the spur-engaging portion or portions of which shall be of suitable strength to afford a 15 proper anchorage for the spurs while the shank portion possesses a desirable degree of flexibility permitting free muscular play of the wearer's foot, while the inner sole presents a smooth foot-bearing surface.

20 The invention consists in the improvements which I will now proceed to describe and claim.

Of the accompanying drawings which form a part of this specification,—

25 Figure 1 represents a bottom plan view of a sporting shoe embodying my invention.

Fig. 2 is a side view of the shoe, a portion of the upper being broken away.

Fig. 3 is a section on line 3—3 of Fig. 1.

30 Fig. 4 is a section on line 4—4 of Fig. 1.

Fig. 5 is a view similar to Fig. 4 showing a slightly different construction.

Fig. 6 is a plan view of the part herein-after called the "shank" piece.

35 Fig. 7 is a section on line 7—7 of Fig. 6 showing also in section portions of the parts herein-after called the "tap" and "heel" pieces.

The same reference characters indicate the 40 same parts in all of the figures.

In the drawings, 12 represents an inner sole having a fore portion, a heel portion and a shank portion, the inner sole being relatively thin and flexible.

45 The upper 13 has an inturned edge portion 13^a which is seated on the under surface of the inner sole by the lasting operation and is secured to the inner sole by means such as lasting tacks, as usual, in preparing the upper and inner sole for attachment to a bottom.

I apply to the lasted upper and inner sole a pieced bottom, including a relatively stiff tap piece 14, a relatively stiff heel piece 15, 55 said pieces being preferably made of sole

leather and spaced apart as shown, and an intermediate shank piece 16 which is relatively flexible and is preferably a piece of cowhide or pigskin.

The opposite end portions of the shank 60 piece 16 overlap the rear and front ends of the tap and heel pieces, and are interposed between said ends and the inner sole. The shank piece is provided at opposite ends of its upper side with skived faces 16^a, as shown 65 by Fig. 7, these faces being arranged to abut against and conform to correspondingly skived faces 14^a and 15^a formed on the upper sides of the contiguous end portions of the tap and heel pieces 14 and 15, as shown 70 by Fig. 7.

The tap, heel and shank pieces are united to form a pieced bottom by fastenings 19, which are preferably chain stitches formed by a suitable sewing machine, the single 75 thread portions of said stitches being laid on the outer surfaces of the tap and heel pieces. Said fastenings extend through the skived faces 14^a, 15^a and 16^a. The pieced bottom is then laid on the superstructure 80 formed by the upper and the inner sole, and united to the fore and heel portions of said superstructure by fastenings 18, which are preferably McKay stitches, and to the shank portion of the superstructure by fastenings 85 18 which may be formed by the same machine which forms the fastenings 19.

The fore and heel portions of the inner sole 12 hold the fastenings 18 and contribute to the stiffness of the tap and heel portions 90 14 and 15. The shank portion of the inner sole constitutes a flexible backing for the shank piece 16, the shank portion of the inner sole and the shank piece 16 collectively forming a two-part shank which is sufficiently 95 flexible and is at the same time of suitable thickness to prevent injury to the wearer's foot.

The skived faces 14^a, 15^a and 16^a are formed and arranged to cause the upper side 100 of the pieced bottom to lie smoothly on the lower side of the inner sole, as shown by Fig. 3, so that the upper or foot-bearing side of the inner sole presents to the foot a smooth surface, which is free from ridges or projections above the portions of the pieced bottom formed by the overlapping of the ends of the shank piece 16 on the contiguous 105 end portions of the tap and heel pieces.

The shoe is provided with the usual cleats 110

22 secured by rivets 23 passing through the tap and heel pieces and through the fore and heel portions of the inner sole.

The fastenings 20 may engage only the 5 shank piece 16 and the inturned portion 13^a of the upper, as shown by Fig. 5, the shank portion of the inner sole 12 being unattached to the shank piece 16 and the portion 13^a.

In practice the tap and heel pieces are 10 united to the shank piece by the fastenings 19 before the pieced bottom is applied to the superstructure formed by the assembled and 15 preliminarily connected upper and inner sole. The pieced bottom thus formed is then secured by the fastenings 18 uniting the tap and heel pieces to the upper and to the fore and heel portions of the inner sole, and by the fastenings 20 uniting the shank piece to the superstructure between the tap and heel 20 pieces, the fastenings 20 engaging the upper and the shank portion of the inner sole, as shown by Fig. 4, or the upper only as shown by Fig. 5.

The connection shown by Fig. 5, is preferred by me, because it provides a maximum degree of flexibility at the shank portion of the shoe. In other words, the shank portion of the shoe is more flexible when the fastenings 20 engage the upper without engaging the inner sole, as shown by Fig. 5, than when said fastenings engage both the upper and the inner sole, as shown by Fig. 4.

It is obvious that a welt may be attached by the usual inseam stitches to the lasted upper and inner sole, said welt, which may be considered as a part of the superstructure, receiving the fastenings 18 which secure the tap and heel pieces to the fore and heel portions of the superstructure and the fastenings 20 securing the shank piece 16 to the shank portion of the superstructure.

The skived rear end of the shank piece 16, reinforces the skived forward end of the heel piece, so that the heel piece 15 has sufficient rigidity at its forward portion to properly support a cleat 22 bearing on the heel piece. The area of the heel piece is relatively small, so that the forward portion of the cleat is necessarily in close proximity to the forward portion or edge of the heel piece. A considerable degree of rigidity at the forward portion of the heel piece is, therefore, desirable.

I claim:—

55 1. A sporting shoe comprising a super-

structure including an inner sole having a fore portion, a heel portion, and a shank portion, and an upper lasted upon the inner sole; a pieced bottom composed of relatively stiff spaced apart tap and heel pieces, and a flexible intermediate shank piece formed to fill the space between the tap and heel pieces; fastenings uniting the ends of the shank piece to the contiguous ends of the tap and heel pieces; fastenings uniting the tap and heel pieces to the upper and inner sole at the fore and heel portions of the superstructure; and fastenings uniting the shank piece to the inwardly turned edges of the upper at the shank portion of the superstructure, between the tap and heel pieces, the last-mentioned fastenings being free from engagement with the shank portion of the inner sole, so that the shank portion of the shoe possesses a maximum degree of flexibility. 75

2. A sporting shoe comprising a superstructure including an inner sole having a fore portion, a heel portion, and a shank portion, and an upper lasted upon the inner sole; a pieced bottom composed of relatively stiff spaced apart tap and heel pieces, having skived faces at the upper sides of their contiguous end portions, and a flexible intermediate shank piece, formed to fill the space between the tap and heel pieces, and having skived faces at the lower side of its end portions, conforming to and overlapped by the skived faces of the said tap and heel pieces; fastenings extending through said skived faces and uniting the skived ends of the shank piece to the contiguous skived ends of the tap and heel pieces; fastenings uniting the tap and heel pieces to the fore and heel portions of the superstructure; and fastenings securing the longitudinal edges of the shank piece at the shank portion of the superstructure, between the tap and heel pieces; the said skived faces causing the upper side of the pieced bottom to lie smoothly on the lower side of the inner sole, so that the foot-bearing side of the inner sole presents a smooth surface to the foot, the skived rear end of the shank piece reinforcing the skived forward end of the heel piece, so that the heel piece has sufficient rigidity at its forward portion to support a cleat bearing on the heel piece. 100 105

In testimony whereof I have affixed my signature.

DANIEL J. GOLDEN.
